UNITED STATES PATENT OFFICE.

HERMAN J. SCHULTZ, OF CHICAGO, ILLINOIS, ASSIGNOR TO W. F. HALL PRINTING CO.,
OF CHICAGO, ILLINOIS, A CORPORATION OF ILLINOIS.

SHEETING MACHINE.

Application filed April 22, 1922. Serial No. 557,110.

To all whom it may concern:

Be it known that I, HERMAN J. SCHULTZ, a citizen of the United States, residing in the city of Chicago, county of Cook, and State of Illinois, have invented certain new and useful Improvements in Sheeting Machines, of which the following is a specification.

This invention relates to improvements in a sheeting machine and refers more particularly to a machine for automatically cutting paper such as wall paper, into predetermined lengths to conform with the design thereon.

Among the objects of the invention are to provide a machine in which a roll of a designed printed paper is fed therethrough and cut by a severing means into predetermined lengths fixed by regulating elements operated from a central position to sever the sheet so that the severed lengths conform with the separate designs printed on the sheet; to provide a machine whereby the rate of feed of the paper may be speeded or retarded at the will of the operator and a secondary compensator operable to retard or advance the sheet to compensate for local irregularities in the design.

Figs. 1 and 2 are side elevational views taken from opposite sides of the machine.

Fig. 3 is an enlarged elevational view of the feeding mechanism.

Fig. 4 is an enlarged view of the intermediate or central portion of the machine.

Fig. 5 is a similar view of the delivery end of the machine.

Fig. 6 is a plan view of the mechanism shown in Fig. 3.

Fig. 7 is a plan view of the mechanism shown in Fig. 4.

Fig. 8 is a plan view of the mechanism shown in Fig. 5.

Fig. 9 is a view taken along line 9—9 in Fig. 7.

Fig. 10 is a view taken along line 10—10 in Fig. 6.

Fig. 11 is a view taken along line 11—11 in Fig. 5.

Figs. 12 and 13 are detailed views showing the operation of the gripper mechanism which delivers the severed sheet to the stack or pile.

In printing wall paper samples, in order to show the complete effect of the side wall and the border combination, rolls of wall paper are printed with the two designs printed on a single roll in a successive pattern so that when the roll is cut and mounted in a sample book form, the buyer can see the effect of the border and side wall pattern on a single sheet.

It has been found on cutting these rolls into separate sheets that the length of the design will vary due either to irregularities in printing or to the character of the paper stock, and from other causes.

The sheeting machine hereinafter explained, is constructed for the purpose of cutting these sheets to conform with the design on the paper roll, the entire operation being regulated by a single operator. Briefly, the machine consists in a mechanism for feeding the paper from a roll over a series of idler rolls and through a cutting mechanism. The paper prior to being cut, is passed over a vertical compensating device which may be raised and lowered to elongate or reduce the vertical loop in the paper so that the speed of the paper may be retarded or accelerated slightly to cause the cutting mechanism to conform with the design on the sheet.

Subsequent to its being severed the sheets are passed between tapes to a gripping mechanism by means of which it is advanced and deposited on a shelf or hopper where a jogger mechanism functions to pile the sheets evenly in a uniform stack from which they are taken to be bound.

Referring to the drawings, the mechanism is mounted upon a standard or frame 1. The paper roll 2 positioned upon a spindle is mounted in a U bearing 3. The sheet 4 from the roll is fed under the guide roll 5 and over a straight edge 6 which serves to break the stock and kill the curl in the paper. From the straight edge, the paper advances over the idler rolls 7 and 8. On top of the latter rolls are positioned slitters 9 which trim the outside edges of the paper removing a narrow strip of unprinted stock or selvage. These slitters are nothing more than circular knives mounted on a shaft 10 which in turn bears in brackets 11 pivoted

to the frame at 12. The sheet passes from the slitter mechanism between the drive or pinch rolls 13 and 14, the former being a rubber surfaced roll mounted on brackets 14^a which are pivoted at 15 and separated from contact with the upper roll by handle 16. The arm 17 integral with the bracket 14^a has a spring 18 connected to its outer end which serves to impose a constant pressure on the paper between the pinch rolls 13 and 14. The upper roll 14 has a knurled steel surface. The sheet then passes vertically over the roll 19 which is vertically adjustable in order to enlarge or diminish the vertical loop of paper. From the roll 19, the paper 4 passes beneath the guide roll 20 through the pinch or friction rolls 21 and 22, the upper roll 21 being a rubber surfaced roll and the lower roll 22 a steel surfaced roll. The lower roll 22 is driven at a faster rate of speed than that at which the paper is traveling, so that any compensation which is made by the vertical adjustment of the loop 4^a will be taken up by the 26 pinch or friction rolls, 21 and 22, and the sheet kept constantly taut.

The friction or pressure exerted upon the paper sheet between rolls 21 and 22 is due to the weight of the upper roll which is mounted in the U bearing 23. The sheet traveling over the friction rolls passes through the severing mechanism which comprises the holder 24 mounted upon the shaft 25. To the holder is fixedly and adjustably mounted a cutting blade 26 which co-operating with the hardened straight edge 27 severs the sheet at desired intervals. A counter-weight 28 serves to increase the smoothness of the cutting operation and prevent undue jar to the mechanism and drive. The severed sheets then pass between the conveyor tapes 29 which run over pulleys 30, the said pulleys mounted on suitable shafts pivoted in the frame.

On the center tape at 31 is situated a means for setting the central tape so that it contacts the sheet and exerts sufficient pressure thereon to cause the sheet to be engaged between the tapes. At the end of 50 the tapes the edge of each oncoming sheet is engaged by grippers 32 mounted upon the chains 33. The grippers consist of contacting piece 32^a and a tumbler 32^b mounted to grip and release the paper sheet as shown in Figs. 12 and 13. The sheets are piled on a stack 34 which is held by an adjustable board or shelf 35. The mechanisms at the side of the piled paper sheets function to keep the sides of the sheets in a regular vertical stack.

The drive of the machine is taken from a motor 36 which drives the pulley 37 through a belt 38. Upon the pulley shaft 39 is the pinion 40 which meshes with the larger gear 41. This gear in turn drives a smaller

gear 42 through a small pinion 43. Upon the same shaft on which the pinion 42 is mounted is a crank arm 44 to which is attached the connecting rod 45 which oscillates the arm 46. This arm manipulates the jogger mechanism as will be hereafter explained in detail. The gear 42 meshes with the gear 47 mounted upon shaft 48. This latter gear drives the pinion 49 shown in Fig. 6 mounted upon a shaft 50 which also carries the sprocket wheel 51. The chain 52 driven by this sprocket drives the cutter mechanism by means of the large sprocket wheel 53. The gear 47 meshes with gear 54 loosely mounted on the shaft 55 which in turn meshes with the idler gear 55 on shaft 58, the latter meshing with the upper pinion of gear 56 fixedly mounted on shaft 59, whose bearings are carried in the frame of the machine. On the two shafts 57 and 59 are mounted tapered cones 60 and 61. These cones are mounted in reverse position so that the large diameter is adjacent to the small diameter of the other as shown in Fig. 6. A belt 62 runs over these cones and is held in contact therewith by adjustable idler pulleys 63.

These pulleys are mounted upon a transversely movable frame or shifter 64 which is operable by means of the threaded screw 65 to move the shifter frame transversely of the machine so that the belt 62 may be moved to either end of the cones. The shifter comprises guide rods 64^a which carry the idler pulleys 63 and are themselves slidably mounted upon the stay rods 66. At the end of the threaded shaft 65 is the mitre gear 67 meshing with a similar mitre gear 68 mounted on regulator 69 which is connected through universal joints 70 to the regulator wheel 71 manipulated by the operator.

The function of this speed regulator is to increase or decrease the speed of the machine so that the sheet will be fed faster or slower as the operator desires. This regulator is used generally in cases where the cutting or severing mechanism continuously fails to sever the sheet at the desired location between the designs, and the discrepancy is continuously in one direction, that is the severing mechanism may continuously sever the sheet short or long in which case by regulating the speed of the machine by the speed regulator the sheets may be severed in their proper position.

It is obvious that when the belt is shifted so that the drive is from the large diameter of one cone to the small diameter of the other, the speed will be increased, while if the belt is shifted in the other direction so that the drive is from the small end of the one cone to the large end of the other cone, the speed will be decreased.

On the opposite end of the shaft 37 on

which the gear 54 is mounted, is the gear 72 which drives a train of gears which operate the lower bed rolls and pinch rolls 14 through the gear 73, as shown in Fig. 1.

5 As explained the compensating mechanism is for the purpose of retarding or advancing the sheet in case of local irregularities in the design while the speed regulator is more commonly used where the severing mechanism continuously cuts ahead or back of the desired position. In case of the cutter failing to sever the sheet at the exact position between the designs the operator turns the hand wheel 74 either one 10 way or the other according to whether he wishes to retard or advance the sheet. This hand wheel is connected through a rod 75 to a worm 76 meshing with the worm gear 77. Also mounted upon the shaft 78 to 15 which the worm gear is fixed, are sprocket wheels 79 which drive similar sprockets 80 by means of the chains 81. To each chain are attached vertically slideable bearings 82 which are slideably mounted upon the vertical rods 83. The bearings 82 carry a transverse shaft on which the roll 19 is mounted. When the hand wheel is turned in one direction the roll is raised on the vertically slideable shaft 83 so that the loop in the 20 paper is made larger thus retarding slightly the travel of the paper as the stock is taken up in the loop. When the hand wheel 74 is rotated in the opposite direction, the vertically slideable roll 19 is lowered and the 25 paper loop decreased in height thus permitting the stock to advance faster, and as explained the lower friction rolls 22 in Fig. 4 traveling at a somewhat faster rate of speed than the paper take up the looseness 30 produced by the lowering of the roll 19 by the compensating mechanism. Under normal conditions, the rate of speed of the roll 22 has only the effect of keeping the sheet taut and feeding uniformly to the 35 cutting mechanism.

The sheet from the compensating loop passes through the friction rolls, thence through the cutter, and is delivered to the conveyor tapes. These upper and lower 40 conveyor tapes are driven through the train of gears meshing with the large gear 84 mounted on the shaft 25 with the cutter as shown in Fig. 4.

At the end of the conveyor tapes the severed sheets are gripped at their forward edge by the gripper mechanism mounted upon the chain 33 shown in Figs. 12 and 13. Contacting stops 32^a are mounted on the shafts 33^b fixed to the traveling chains 45 above the surface of the sheet and tumblers 32^b are pivoted at 32^c on lugs likewise attached to the chains.

As the chains running over the sprocket wheels 85 advance the tumbler mechanisms to a position shown in Fig. 12, the machine

drive is so timed that the severed sheet will be in a position on the tapes as shown in the same figure, ready to be engaged by the gripper mechanism. The tumbler mechanism as it advances, has its lower depending leg 32^d contacted by a pin 86 on the arm 87. This rotates the tumbler about the pivot shaft 32^c inverting the position of the tumbler and causing the enlarged head of the tumbler to rotate about the pivot 32^c as 70 an axis and grip the edge of the paper sheet between the head of the gripper and the contacting stop 32^a as shown in dotted lines in Fig. 12. In this position the sheet it withdrawn from the tapes and carried to 75 a position over the paper stack or pile of severed sheets 34, at which time the second leg 32^e which is set at an angle of approximately 50° with the leg 32^d is contacted by pins 88 on the arms 89 rotating the tumblers 80 to their former position out of contact with the stop 32^a as shown in dotted lines in Fig. 13. The gripper mechanisms then rotate with the chains back to a position to grip 85 the next oncoming sheet while the sheet falls upon the stack. The gripper mechanism is driven by a drive chain 33^a from the sprocket 25^c mounted upon the shaft 25 to which the cutting mechanism is fixed as shown in Figs. 1 and 7. Thus the entire 90 machine operates in timed relation. The tumbler mechanisms are fixed to the chains by the pivot rods 32^c and 32^e.

The shelf or holder upon which the sheets are stacked may be lowered by means of the handle 90 which through a worm meshing with the worm gear 91 mounted on the shaft 92 rotates the shaft in either direction and serves to raise or lower the chains 93 and 94 running over sprockets mounted 95 on the frame of the machine and serving to raise or lower the carrier shelf 35.

The jogger mechanism which is operated through the connecting rod 45 and arm 46 gives the side guides 95 between which the severed sheets are piled, an oscillating movement functioning to stack the sheets evenly, the pile thus having straight vertical edges and making it easier to handle the sheets and aiding in the subsequent binding operation. The details of the jogger mechanism are shown more clearly in Fig. 11, the oscillating arm 46 giving the shaft 96 a like movement which is transmitted to similar shafts 97 through the mitre gears 98. Depending arms 99 fixed to the shafts contact lugs 100 mounted upon the movable members 101. These movable members are fastened by spring 102 to the fixed brackets 103, thus as the guides 95 are attached to the movable members 101 when the latter are moved by the contacting of the lugs by the depending arms, the guide plates 95 will be given an oscillating movement similar to that of the depending elements 99 105 110 115 120 125 130

due to the slideable motion given the movable member 101 by the depending arms and springs 102. It will be noted in Fig. 8 that the side shaft 97 along one side of the machine transmits the oscillating movement to one side guide while the shaft on the opposite side of the machine transmits the oscillating movement both to the side guide and to the end guide plate, through the short shaft 104.

I claim as my invention:

1. In a sheeting machine the combination with means for feeding a design printed paper sheet from a roll, of a severing mechanism for cutting the sheet into predetermined lengths, a speed regulator comprising two oppositely positioned belt driven cones operable to control the rate of travel of the sheet, a loop compensating mechanism comprising means for increasing or decreasing the size of paper loop for retarding or advancing the sheet to compensate for irregularities in the design, conveyor means adapted to carry the severed sheets from the cutting mechanism and gripping mechanism operable to deposit the severed sheets on the stack, a jogger mechanism for stacking the severed sheets delivered from the gripper mechanism in a straight sided pile.

2. In a sheeting machine the combination with means for feeding a design printed paper sheet from a roll, of a severing mechanism operating in timed relation therewith for cutting the sheets into regular predetermined lengths, a speed regulator operable to accurately control the travel of the sheet, a loop compensating mechanism operable to increase or decrease the length of travel of the sheet and functioning to compensate for minor irregularities in the design, means for conveying the severed sheets from the cutting mechanism.

3. In a sheeting mechanism the combination with means for feeding a design printed paper sheet from a roll, of a severing mechanism operating in timed relation therewith for cutting the sheet into predetermined lengths, a speed regulator and loop compensator, said speed regulator operable to control the rate of travel of the paper sheet the loop compensator functioning to advance or retard the paper sheet whereby the sheet's travel is compensated for minor irregularities in the design, producing accurate severance of the sheet intermediate the printing designs, a means for conveying the printed sheets from the cutting mechanism.

4. In a sheeting machine, the combination with a continuously forward moving paper sheet, of a severing mechanism operating in timed relation therewith for cutting the sheet into predetermined lengths, an independently controlled speed regulator to accurately control the travel of the sheet, a compensating mechanism operable to in-

crease or decrease the length of travel of the sheet and also independently controlled, a conveyor for removing the severed sheets from the cutting mechanism having a spring tensioned contacting piece and stud, between which the severed sheets are gripped, said gripper mechanism being engaged and disengaged by tripping means contacting therewith at predetermined points in its travel.

5. In a sheeting machine, the combination with means for feeding a paper sheet, of a severing mechanism operating therewith for severing the sheets into predetermined lengths manually adjustable compensating mechanism operable to change the path of travel of the sheet to increase or decrease the length of travel of said sheet before being engaged by the severing mechanism, and means for removing the severed sheets.

6. In a sheeting machine, the combination with means for feeding a paper sheet, of a severing mechanism operating therewith for severing the sheet into predetermined lengths an independently controlled speed regulator to accurately control the travel of the sheet, manually adjustable compensating mechanism operable to change the path of travel of the sheet to increase or decrease the length of travel of said sheet before being engaged by the severing mechanism, and means for removing the severed sheets.

7. In a sheeting machine, the combination with means for continuously feeding a paper sheet, of a severing mechanism having a cutter for cutting the sheet into uniform lengths, a manually adjustable compensating mechanism for varying the path of travel of the sheet to alter its distance of travel before delivery to the severing mechanism and means for removing the severed sheets.

8. In a sheeting machine, the combination with means for continuously feeding a paper sheet, of a severing mechanism having a continuously rotating cutter for cutting the sheet into uniform lengths, a manually adjustable compensating mechanism between the feeding means and severing mechanism for varying the path of travel of the sheet to alter its distance of travel, and means for removing the severed sheets.

9. In a sheeting machine, the combination with means for continuously advancing a sheet, of a severing mechanism operating in timed relation therewith for severing the sheet into uniform lengths, an independently controlled speed regulator to accurately control the travel of the sheet, an independently controlled compensating mechanism operable to vary the path of travel of the sheet, a conveyor for removing the severed sheets, gripping mechanism on said conveyor and tripping means for engaging and disengaging said gripping mechanism for the purpose described.

10. In a sheeting machine, the combination with means for continuously feeding a paper sheet, of a severing mechanism having a cutter for cutting the sheets into predetermined lengths, a manually controlled independent compensating mechanism between the feeding mechanism operable to vary the path of travel of the sheet and the severing mechanism to deliver the sheet to the severing mechanism at the time of the severing operation in uniform lengths, and means for removing the severed sheets.

HERMAN J. SCHULTZ.
